FILLING THREAD CUTTER FOR WEFT
REPLENISHING LOOMSGabriel C. Beatrice, Shrewsbury, Mass., assignor
to Crompton & Knowles Loom Works, Worcester,
Mass., a corporation of Massachusetts

Application May 29, 1948, Serial No. 29,967

5 Claims. (Cl. 139—267)

1

This invention relates to improvements in thread cutters for weft replenishing looms and it is the general object of the invention to provide means by which the thread cutter adjacent to the shuttle eye may be adapted for use with a variety of forms of shuttle boxes.

On a weft replenishing beat of a loom it is desirable to cut the thread of the outgoing bobbin so that it can be removed and not be drawn into the warp shed. On a type of loom which has gone into general use this cutting is effected by a cutter mechanism of the scissor type including a blade fixed to the mechanism and another blade pivoted thereto. When operating these blades enter a slot in the front wall of the shuttle box and then pass into an opening in the front wall of the shuttle to cut the thread which leads back from the shuttle eye to the selvage. The cutter moves laterally during the cutting operation and any interference with its lateral movement will adversely effect the cutting operation. When a thread cutter of this type is applied to various types of looms it is found that considerable difficulty is experienced in adapting the cutter for correct entry into the slot of the front wall of the shuttle box to avoid the aforesaid interference. It is an important object of the present invention to provide means by which the normal position of the pivoted cutter blade can be adjusted so that it can enter the slot in the box front without engaging the latter and therefore be free to move laterally.

The means for operating the movable cutter blade includes a roll adapted for engagement with a surface on the front of the lay. This roll is ordinarily mounted on the lower part of the pivoted cutter blade and whenever the blade is adjusted to clear the shuttle box front the roll has a corresponding motion either from or toward the lay, depending upon whether the cutting jaw of the upper cutter blade is lowered or raised by its adjustment. This movement of the roll alters the time of its engagement with the lay and therefore of its operation. It is a further object of the invention to provide means by which the roll may be mounted on but moved relatively to the pivoted cutter blade to compensate for the movement of the blade effected by the first named adjustment, thereby maintaining the correct timing for the cutting operation.

In thread cutters of the type to which the invention more particularly relates there is a tendency for the thread cutting jaws to overlap each other to such an extent as to interfere with their free relative motion. It is another object of the

2

invention to provide means which will prevent objectionable angular displacement of the pivoted cutter blade to the end that the latter may always be held in such position that its cutting jaw can move freely with respect to the cutting jaw of the fixed blade.

With these and other objects in view which will appear as the description proceeds, the invention resides in the combination and arrangement of parts hereinafter described and set forth.

In the accompanying drawings, wherein a convenient embodiment of the invention is set forth,

Fig. 1 is a side elevation partly in section of part of a weft replenishing loom having the invention applied thereto.

Fig. 2 is a plan view looking in the direction of arrow 2, Fig. 1.

Fig. 3 is an enlarged side elevation of the thread cutter in open position and looking in the direction of arrow 3, Fig. 2, adjacent parts of the lay and parts thereon being in section.

Figs. 4 and 5 are enlarged vertical sections on lines 4—4 and 5—5, respectively, of Fig. 3, and

Fig. 6 is a view similar to Fig. 3 but showing the cutter closed as it appears at the end of a cutting operation.

Referring particularly to Figs. 1 and 2, the loom frame 10 supports a reserve bobbin magazine M including in its construction a transerrer arm 11 pivoted as at 12. The magazine in the present instance is provided with front and back stacks 13 and 14 of reserve bobbins which move by gravity to transfer position. The magazine can rock so that the lowest bobbin in either stack will be under the foot 15 of the transerrer arm at the time of replenishing operation. A transerrer latch 16 mounted on a latch holder 17 pivoted as at 18 to the transerrer arm is normally in the down position shown in Fig. 1 to clear the transfer bunter 19 on the lay L.

Secured to stud 12 is a stand 25 receiving a stem 26 held in adjusted vertical position by an adjusting set screw 27. A lever 28 is pivoted to the bottom of stem 26 to swing in a horizontal plane and is acted upon by a spring 30 which normally tends to move the right hand arm 29 thereof as viewed in Fig. 2 rearwardly or toward the lay L. The left hand arm 31 of lever 28 is normally urged forwardly by spring 30 against 50 a control stop 32 on the transerrer arm. At the time of a weft replenishing operation latch 16 is raised and then moved forwardly by bunter 19 and the stop 32 due to its forward movement permits left hand or counter-clockwise rocking 55 of lever 28 as viewed in Fig. 2 under the action

of spring 30, thereby effecting rearward movement of arm 29.

Lever 28 has a hub 34 which receives a rod 35 the rear end of which is secured in a laterally offset lug 36 of a support 37, see Fig. 2. The support carries the cutter unit mechanism C which includes a cutter blade 38 fixed to support 37 and a second cutter blade 39 pivotally mounted on stud 40 extending through blade 38 and tapped into support 37. Blade 39 has upper and lower forwardly extending stop arms 41 and 42 which are above and below, respectively, the lug 36. Fixed blade 38 has a rearwardly extending lower cutting jaw 43 which cooperates with a similar upper cutting jaw 44 extending rearwardly from the pivoted blade 39.

The lay L has a shuttle box 45 to receive a shuttle S carrying a bobbin B. The shuttle box has a box front 46 having a slot 47 therein to receive the cutting jaws 43 and 44. Slot 47 registers with a slot 48 in the front wall of the shuttle when the latter is boxed. These slots receive the jaws 43 and 44 on a weft replenishing operation of the loom as indicated in Figs. 3 and 6. The filling thread F extends from the bobbin B through the shuttle eye E and along the front wall of the shuttle to the adjacent cloth and preparatory to a thread cutting operation thread F will enter the bight between the top and bottom cutting jaws as indicated in Fig. 3.

The lay may be provided with a cutter operating plate 50 for engagement with a roll 51 supported on the pivoted blade 39 in a manner to be described hereinafter. A relatively weak tension spring 52 between arm 41 and lug 36 tends to normally to hold the blade 39 in the open position shown in Fig. 3.

On non-replenishing beats of the loom the cutter mechanism C will be held in the normal forward inactive position shown in Fig. 2 by engagement of lever arm 31 with stop 32 on the transfer arm. When the latter descends on a bobbin changing beat of the loom stop 32 moves forwardly and spring 30 rocks lever 28 in a counter-clockwise direction as viewed in Fig. 2 to move the cutter mechanism rearwardly to operating position and locate the jaws 43 and 44 for entry into the aligned slots 47 and 48. As the lay advances plate 50 engages roll 51 to rock blade 39 against the action of spring 52 to cause cutting of the filling thread F. This rocking or blade 39 relatively to the support 37 is limited by engagement of the lower arm 42 with the lug 36, after which continued forward movement of the lay causes the cutter mechanism C to swing around the axis of lever 28 in a clockwise direction as viewed in Fig. 2, thereby effecting movement of the cutter mechanism which is partly to the right as viewed in Fig. 2 in the direction of the length of the lay, and partly forward. It will be understood that the jaws 43 and 44 can move laterally or toward the outer end of the lay only if they are out of engagement with the box front 46 and the shuttle S.

The matter thus far described, except as will be pointed out hereinafter with particular reference to the control and adjustment of cutter blade 39 and the mounting of roll 51, may be the same as that set forth in prior patent to Turner No. 2,398,264.

In carrying the present invention into effect lug 36 is provided with a vertical adjusting screw 55 having a head 56 for engagement with arm 41 on pivoted cutter blade 39. As shown in Fig. 5 adjusting screw 55 is tapped vertically into the

lug 36 and is held in adjusted vertical position by a set screw 57 which forces a plug 58 of relatively soft metal against the adjusting screw 55. By raising the stop screw 55 the normal position of blade 39 can be altered to enable the jaw 44 to be lowered to clear that part of the box front 46 at the top of slot 47. This adjustment for arm 41 does not interfere in any way with the normal engagement of arm 42 and lug 36 during a cutting operation.

The previously described roll 51 is rotatably mounted on a carrier 60 having a slot 61 in the upper surface thereof to receive the lower edge of cutter blade 39. A carrier supporting and adjusting screw 62 is threaded through a supporting foot 63 fast with respect to lower arm 42, and screw 62 extends rearwardly into a clear hole 64 in the carrier 60 and is provided with a peripheral groove 65 which receives a holding or retaining pin 66 driven through the carrier 60. Screw 62 is not tapped into hole 64 but can turn freely therein. Turning of the screw 62 in the foot 63 will cause the carrier 60 to slide along the lower edge of blade 39 in a direction depending upon the direction in which screw 62 is turned. The latter by its entry into hole 64 supports the carrier 60 and roll 51 as shown in Fig. 6, and the lower edge of blade 39 by its entry into slot 61 prevents substantial angular movement of the carrier around the axis of adjusting screw 62.

If it should be necessary to effect adjustment of the normal position of blade 39 in a clockwise direction as viewed in Figs. 3 and 6, stop screw 55 will be turned to move upwardly, thereby raising the lowest position which arm 41 can occupy and correspondingly lowering the highest position which jaw 44 can occupy. It will be noted, however, that when blade 39 is adjusted in this manner the cutter operating roll means comprising carrier 60 and roll 51 moves forwardly, or to the left as viewed in Fig. 6. This change in roll 51 to a position forward of its previous position will cause delayed operation of the cutting mechanism as the lay advances. To prevent this delay a compensating adjustment of the roll is effected by turning screw 62 in such a direction as to move the roll 51 rearwardly relatively to the blade 39. To effect this adjustment the lay can be moved to the position which it occupies when it is desired to have the cutting operation start, and screw 62 can then be turned to move the roll rearwardly until it engages plate 50.

If a reverse adjustment of blade 39 is desired, requiring downward threading of stop screw 55 in lug 36, roll 51 will move rearwardly from its previous position, but this can be corrected by a forward threading of screw 62.

Another feature of the invention relates to the yielding mounting of pivoted blade 39 and is shown more particularly in Fig. 4. The stud 40 has a head 70 larger than that part thereof which passes through fixed blade 38 and is threaded into the head 37. A sleeve 72 surrounds the head 70 and has an annular flange 73 the plane of which is substantially perpendicular to stud 40, or parallel to blade 38. A compression spring 74 around the sleeve is located between the head 75 of the stud 40 and flange 73 and urges the latter to the left as viewed in Fig. 4 to hold flange 73 against the blade 39 and cause the blades 38 and 39 to maintain face to face engagement. In this way the jaws 43 and 44 are kept in correct cutting position. The length of the sleeve 72 is slightly less than the length of that part of the head 70 between flange 73 and the stud head 75

so that a slight endwise movement of the sleeve can be effected as jaw 44 moves down along jaw 43. This movement, however, is very small and the sleeve will engage the stud head 75 to prevent any substantial angular twist of the blade 39 and the jaw 44 relatively to the jaw 43. These two jaws are therefore held in correct position for free relative movement.

From the foregoing it will be seen that simple means have been provided by which the normal position of pivoted cutter blade 39 may be adjusted with respect to the cutting mechanism to adapt it for use with various kinds of shuttle box front walls. It will also be seen that when an adjustment is made to adapt the cutter for a particular box front the adjusting screw 62 can be altered to compensate for any horizontal movement of roll 51 incident to angular adjustment of blade 39. It will be seen that the adjustment for arm 41 does not interfere with the normal movement of arm 42 in limiting downward movement of jaw 44. The carrier 60 is supported at the rear end of adjusting screw 62 and is prevented from having angular movement relatively to the screw by entry of the lower part of blade 39 into the slot 61. Furthermore, it will be noted that the sleeve 72 cooperates with the head 75 of the stud 40 to prevent any substantial angular movement of the pivoted blade 39 with respect to the fixed blade 38.

Having thus described the invention it will be seen that changes and modifications of the foregoing specific disclosure may be made without departing from the spirit and scope of the invention.

What is claimed as new is:

1. A weft thread cutting unit for a loom, said unit comprising a support formed with a lateral lug and having a cutter blade fixed thereto, a second cutter blade pivotally mounted on said support and having upper and lower arms on opposite sides of said lug, an adjustable stop screw on said support to engage said upper arm to vary the position of said second blade relatively to the fixed blade when said upper arm engages the stop screw, operating roll means for the second blade, and an adjusting screw supported by the lower arm and operatively connected to and supporting said roll means and rotatable relatively to said second blade to vary the position of the roll means relatively to said second blade.

2. A weft thread cutting unit for a loom, said unit comprising a support formed with a lateral lug and having a cutter blade fixed thereto, a second cutter blade pivotally mounted on said support and having upper and lower arms on opposite sides of said lug, and an adjustable stop screw for the upper arm on said support to vary the position of said second blade relatively to the fixed blade when said upper arm engages the stop screw.

3. In weft thread cutting mechanism for a loom having a lay provided with a shuttle box

front wall formed with an opening, a support mounted for forward movement by the lay and in a direction lengthwise of said front wall, said support having a lateral lug and having fixed thereto a cutter blade formed with a rearwardly extending cutting jaw to enter said opening, a second cutter blade, a pivotal mounting on said support for said second blade, a second rearwardly extending cutting jaw on said second blade to enter said opening for cooperation with the jaw of the fixed blade and having also upper and lower forwardly extending spaced arms, one above and the other below said lug, a vertical adjusting screw in said support for engagement with one of said arms to determine the upper limit of movement of said second jaw to prevent the latter from engaging said front wall at the top of said opening, lay engaging roll means for the second blade below said pivotal mounting, and a horizontal adjusting screw supported on said lower arm and extending into supporting relation with said roll means and effective when turned to change the back and forth position of the roll means relatively to the lay.

25 4. A cutter blade for the filling thread cutting mechanism of a loom having a lay, said blade comprising a flat metallic body formed with a thread cutting jaw and a substantially straight edge on the periphery of the body below said jaw, an adjusting screw, a lug fixed to the blade in which the screw is threaded, a lay engaging roll, and a carrier on which the roll is rotatably mounted operatively connected to and supported by said screw and formed to cooperate with said straight edge to move therealong as the screw is turned in said lug.

30 5. A cutter blade for the filling thread cutting mechanism of a loom having a lay, said blade comprising a flat metallic body formed with a thread cutting jaw and a substantially straight edge on the periphery of the body under said jaw, a carrier having a groove therein receiving said straight edge, a lay engaging roll rotatable on said carrier, and an adjusting screw supported by and rotatable relatively to the blade and operatively connected to said carrier and effective when turned relatively to the blade to move said carrier along said straight edge.
